UNITED STATES PATENT OFFICE.

JOHN G. DAHL, OF OMAHA, NEBRASKA.

DESIGN FOR A LAMP-LENS.

51,585.

Specification for Design. **Patented Dec. 18, 1917.**

Application filed October 27, 1917. Serial No. 198,873. Term of patent 3½ years.

To all whom it may concern:

Be it known that I, JOHN G. DAHL, a citizen of the United States, residing at Omaha, in the county of Douglas and State of Nebraska, have invented a new, original, and ornamental Design for a Lamp-Lens, of which the following is a specification, reference being had to the accompanying drawing, forming a part thereof.

The figure is a plan view of a lamp-lens, showing my new design.

I claim:

The ornamental design for a lamp-lens, as shown.

In testimony whereof, I have affixed my signature in presence of two witnesses.

JOHN G. DAHL.

Witnesses:

NEIRAM A. STURGES,
ARTHUR H. STURGES.
